UNITED STATES PATENT OFFICE

2,455,016

LATH BOARD

George A. Buttress, Los Angeles, Calif.

Application April 11, 1944, Serial No. 530,538

3 Claims. (Cl. 72—124)

1

This invention relates to a lath board and particularly pertains to lath board of the type embodying a layer of a plaster composition interposed between cover sheets of fibrous material such as paper and in which the board is formed with a series of apertures to receive and effect a bond with plaster applied to the face of the board.

The invention contemplates and has as one of its objects the provision of a construction whereby the portions of the outer fibrous cover sheet surrounding apertures in the sheet will be turned inwardly to overlie the outer end portions of the walls surrounding the apertures in the plaster layer and be at least partially imbedded therein so as to anchor the portions of the cover sheet surrounding the holes in the sheet in the plaster layer and reinforce the outer margin of the walls of the plaster-receiving aperture and at the same time present a neat and finished appearance.

Another object of the invention is to provide a construction at the inner end of the plaster-receiving apertures which while allowing a portion of applied plaster entering the apertures to pass through the board, will inhibit or restrict the flow of the plaster through the apertures in a fashion to obviate or at least minimize waste of plaster due to flow of excessive quantities of the plaster through the apertures.

A further object is to provide a construction in the back cover sheet whereby it is reinforced around the holes therein.

With the foregoing objects in view, together with such other objects and advantages as may subsequently appear, the invention resides in the parts and in the combination, construction and arrangement of parts hereinafter described and claimed, and illustrated by way of example in the accompanying drawing, in which:

Fig. 1 is a view in elevation of a fragmentary portion of a lath board as constructed in accordance with the invention;

Fig. 2 is an enlarged detail in section taken on the line 2—2 of Fig. 1 showing the manner of forming the plaster-receiving apertures;

Fig. 3 is a view of a fragmentary portion of the board as seen from the back thereof showing the manner of reinforcing the backing cover sheet around holes formed therein;

Fig. 4 is a view in vertical section showing the manner in which plaster is applied to the face of the board and as occupying the plaster-receiving apertures.

Referring to the drawings more specifically, A indicates generally a lath board comprising a layer 5 of plaster interposed between a pair of

2

fibrous cover sheets including a front cover sheet 6 and a back cover sheet 7; the board A being formed with a series of apertures B for the reception of plaster. The essence of the invention resides in a mode of fashioning the plaster-receiving apertures B.

In carrying out the invention the cover sheets 6 and 7 are formed with holes 8 and 9 respectively which are smaller than the holes 10 in the plaster layer 5 crosswise thereof, which holes 8, 9 and 10 are centered relative to each other and are designed to collectively form the plaster-receiving apertures B.

In forming the board the margins of the holes 8 in the front cover sheet 6 are turned inwardly and downwardly into the outer ends of the holes 10 to extend over and be partially imbedded in the outer ends of the plaster layer 5; the marginal portions 11 of the holes 8 being curved inwardly and then spread outwardly to provide rounded margins 12 at the outer ends of the apertures B. In order that the marginal portions 11 conform to the enlargement of the holes 10 the margins 11 split under strains imposed thereon during stretching thereof in the operation of expanding the margins 11 thus forming the margins 11 with a series of tongues or flaps 14 which are readily partially imbedded in and engaged by the plaster layer 5. In this fashion the walls surrounding the apertures B are formed with beaded fibrous outer margins, whereby such margins are reinforced, anchorage of the marginal portions of the cover sheet surrounding the holes 8 in the cover sheet 6 is effected and a neat and finished appearance is attained.

The marginal portion 15 of the back cover sheet 7 surrounding the holes 9 in the latter project transversely into the inner ends of the holes 10 and project from the inner margins of the walls 40 surrounding the latter. The marginal portions 15 thus form inwardly projecting fibrous flanges at the inner ends of the apertures B, such as to oppose the flow of plaster through the apertures B and yet allow a modicum of plaster to pass to the back of the board through the openings 9 in the back cover sheet to effect anchorage of the latter as indicated in Fig. 4.

In order to reinforce the marginal portions 15 and strengthen them against being pressed away from the inner margins of the walls surrounding the holes 10 they are curved in section with their inner margins extended into the holes 10 toward the outer ends thereof.

Annular ribs 16 are formed on the back cover sheet 7 in slightly spaced relation to the base

portions of the marginal flanges 15, which ribs are pressed into the layer 5 so as to be imbedded therein around the inner margins of the holes 16. The sides of the ribs 16 formed in continuation of the margins 15 afford curved extensions of the latter so as to impart arcuate cross sections to the portions of the back cover sheet extending between the ribs and the holes 9 whereby the margins of the latter are further strengthened against being pressed outwardly on being subjected to the pressure of plaster directed into the apertures B.

In order to effect imbedding of the inturned flanges 11 or flap 14 and the reinforcing ribs 16 in the plaster layer 5, they are pressed into the plaster layer while the latter is in a soft or plastic state and while the fibrous cover sheets are in a moist state.

The apertures B are preferably circular and the holes 10 are preferably tapered to diverge outwardly from the front cover sheet 6 toward the back cover sheet 7.

On applying a plaster body C to the face of the board as shown in Fig. 4, portions of the plaster will enter the apertures B and in so doing will displace air in the latter which passes to the back of the board through the holes 9 so as to permit complete filling of the apertures with the plaster, while a small portion of the plaster will be passed through the holes 9 and will flow over the outer faces of at least portions of the marginal portions 15 of the cover sheet surrounding the holes 9 such as to anchor the portions 15 in the applied plaster as indicated at 17 in Fig. 4, thus effecting a bond between the applied plaster and the marginal portions 15 of the sheet surrounding the holes in the back cover sheet.

By forming the front cover sheet 6 with the inturned margins 11 surrounding the holes 8 and by providing the annular ribs 16 around the holes 9 in the back cover sheet 7 the cover sheets and the assembled board are strengthened against bending across the weakened areas or lines occasioned by removal of the material necessary in forming the apertures B. This enables the formation of the apertures B of larger cross section relative to the thickness of the board than would otherwise be practical, and also enables placing the holes closer together than is ordinarily done so as to increase the number of plaster bonding points in a given area.

I claim:

1. In a lath board embodying a plaster layer interposed between a fibrous front cover sheet and a back cover sheet having plaster-receiving apertures extending therethrough formed by axially aligned holes in said sheets and plaster layer, the construction in which the marginal

portions of the back cover sheet surrounding the holes in said sheet project transversely from the adjacent margins of the walls surrounding the holes in the plaster layer into the path of plaster delivered to the apertures to restrict flow of plaster through the apertures; the projecting marginal sheet portions surrounding the holes in the back cover sheet being curved in section into the holes in the plaster layer to oppose thrust of plaster pressed thereagainst from the interior of the holes in the plaster layer.

2. In a lath board having a layer of plaster and a fibrous back cover sheet with axially aligned holes in the cover sheet and plaster layer forming plaster receiving holes through the lath board, the back cover sheet being formed with arcuate ribs which encircle the holes therein and in the plaster layer, said ribs being directed into and embedded in the plaster layer with portions of the back cover sheet projecting inwardly from the ribs into the holes of the plaster layer.

3. A lath board in which a plaster layer is interposed between a front cover sheet and a fibrous back cover sheet and having plaster receiving apertures therein comprising holes leading through the plaster layer and through the cover sheets in axial alignment with each other, the holes in the plaster layer being tapered from the back cover sheet toward the front cover sheet, the marginal sheet portions surrounding the holes in the front cover sheet being turned inwardly against the walls surrounding the holes in the plaster layer, the back cover sheet having annular ribs which encircle the holes therein and in the plaster layer and are directed into and embedded in the plaster layer with portions of the back cover sheet projecting inwardly from the ribs and into the holes of the plaster layer.

GEORGE A. BUTTRESS.
